UNITED STATES PATENT OFFICE.

HENRY L. BROWER, OF NEW YORK, N. Y.

IMPROVEMENT IN BURGLAR-ALARMS.

Specification forming part of Letters Patent No. 136,210, dated February 25, 1873.

To all whom it may concern:

Be it known that I, HENRY L. BROWER, of the city, county, and State of New York, have invented a new and Improved Burglar-Alarm, of which the following is a specification:

My invention consists of a small, light, portable, and ornamental alarm or call-bell, so contrived that the devices for restraining or holding the clock-mechanism used for actuating the bell-hammer in check will be caused to release the said mechanism and allow it to act, if the alarm be lifted from the table or other support, or if a knob be lifted or pulled, or turned to the right or left, so that the alarm will be useful in banks and other places to protect papers or other valuables temporarily, simply by being placed on them; also, for a burglar-alarm by attaching small threads or cords to the knob, and arranging said threads so that the opening of a window or door, or the passing through an open door or window, or other passage by a person will, by his coming against the cords or threads pull the knob or turn it, and thereby set the alarm in motion; also, for a fire-alarm by having weights or springs let go by the burning of the threads to pull or turn the knob and liberate the sounding mechanism, all as hereinafter described.

Figure 1 is a longitudinal sectional elevation of my improved alarm taken on the line *x x* of Fig. 2. Fig. 2 is a plan view; and Fig. 3 is a partial transverse section taken on the line *y y* of Fig. 2.

Similar letters of reference indicate corresponding parts.

A is a small metal or other case of any suitable form or size, inclosed at the sides and top, but open at the bottom, containing a bell, *B*, bell-hammer *C*, and a clock mechanism, *D*, for actuating the hammer, all of which may be constructed and arranged in any approved way. *D'* is a stop or detent for holding the arm of the bell-hammer in check, and for being raised to liberate the hammer to allow it to sound the alarm, by the lifting of the apparatus from the table or other object or objects whereon it may rest, or by pulling or turning the knob-spindle, as aforesaid. This detent is fixed on a spring, *E*, which is fastened to the case at one end, so that when in

its natural posture it will hold the detent across the path of the arm of the bell-hammer and prevent it from working. *F* represents a couple of inclined planes arranged on this spring reversely to each other. *G* is an arm projecting from a spindle, *H*, at right angles thereto, the said spindle projecting downward through the top of the case and a base piece, *I*, from a knob, *K*, for which the base *I* is provided as a rest, the said spindle being capable of oscillating right and left on its axis, also of moving up and down a short distance. This arm *G* ranges under the spring *E*, or on that side which is in the direction of the movement of the spring when it engages the bell-hammer, which is also the side whereon the inclines *F* are arranged, so that by the oscillation of the knob and its spindle in either direction, the detent will be moved away from the arm of the bell-hammer and liberate it by the action of the arm *G* on the inclines, and it will move back and check the said bell-hammer when the knob and spindle are turned to the front where the inclines meet, as represented in Fig. 1. The spring will also be raised and the bell-hammer liberated by pulling the knob and spindle upward by the action of the arm *G*, which will lift the spring.

In order to cause the sounding of the alarm by lifting the apparatus off its seat on a table, pile of papers, or other objects, a spring, *L*, and a lever, *M*, are combined with the spring *E*, so as to lift the detent away from the bell-hammer, when not prevented, and a short rod or pin, *N*, is arranged in a suitable support, *O*, and in connection with the lever *M*, so that when the case is set on the table the rod is pushed up and prevents the lever *M* from acting on the spring *E*; it also lifts the spring *L*, so that immediately on the lifting of the case from the table said spring will force the spring *L* up through the medium of the lever *M*, and thereby liberate the bell-hammer.

The cords used when the instrument is to be employed as a burglar-alarm will be attached to the rings of the knob so as to turn it when they are pulled, or they may be attached to the top so as to lift it. When used as a call-bell, the knob is lifted to liberate the bell-hammer.

The knob and knob-stand, also the case, may be in any approved ornamental design. P is a key for locking the bell-hammer by the arm Q when it is desired not to have the alarm liberated in any way. Said key is introduced from the top of the case through the letter R.

Having thus described my invention, I claim as new and desire to secure by Letters Patent—

1. The detent D', spring E, inclined planes

F F, arm G, spindle H, and knob K, combined and arranged with respect to the alarm mechanism in the case A, to operate substantially as and for the purpose described.

2. The combination, with spring E, of the spring L, lever M, and pin N, as and for the purpose described.

HENRY L. BROWER.
